(57) **CLAIM**

The ornamental design for a television set with optical disc memory, as shown and described.

DESCRIPTION

FIG. 1 is a front view of a television set with optical disc memory showing our new design;

FIG. 2 is a top plan view thereof;

FIG. 3 is a bottom plan view thereof;

FIG. 4 is a left side view thereof;

FIG. 5 is a right side view thereof;

FIG. 6 is a rear view thereof;

FIG. 7 is a perspective view thereof;

FIG. 8 is a perspective view thereof in a state that a tray of the optical disc memory is drawn out;

FIG. 9 is a right side view of a first modified example of the television set with optical disc memory;

FIG. 10 is a perspective view of FIG. 9;

FIG. 11 is a right side view of a second modified example of the television set with optical disc memory;

FIG. 12 is a perspective view of FIG. 11;

FIG. 13 is a right side view of a third modified example of the television set with optical disc memory;

FIG. 14 is a perspective view of FIG. 13;

FIG. 15 is a right side view of a fourth modified example of the television set with optical disc memory;

FIG. 16 is a perspective view of FIG. 15;

FIG. 17 is a right side view of a fifth modified example of the television set with optical disc memory; and,

FIG. 18 is a perspective view of FIG. 16.

The broken lines shown in FIGS. 1-18 are for illustrative purposes only and form no part of the claimed design.
